UNITED STATES PATENT OFFICE.

DANIEL DRAWBAUGH, OF EBERLY'S MILL, ASSIGNOR OF ONE-HALF TO
EDGAR W. CHELLIS, OF HARRISBURG, PENNSYLVANIA.

HYDRAULIC JACK.

SPECIFICATION forming part of Letters Patent No. 288,697, dated November 20, 1883.

Application filed June 21, 1882. (No model.)

To all whom it may concern:

Be it known that I, DANIEL DRAWBAUGH, of Eberly's Mill, Cumberland county, Pennsylvania, have invented new and useful Improvements in Hydraulic Jacks, of which the following is a full, clear, and exact description and specification.

The objects of my improvements are, first, the construction of cheaper, lighter, and stronger hydraulic jacks, and economy of space in the same; second, the construction of hydraulic jacks in such manner that parts thereof may be removed when injured and other parts substituted therefor cheaply and quickly; third, that by substitution of cheap parts (while the more expensive parts are retained) hydraulic jacks may be lengthened or shortened, and thus adapted to different kinds of work; fourth, providing better pump mechanism; fifth, providing better packing for such parts of hydraulic jacks as require the same. These objects I attain by means of the mechanism illustrated in the accompanying drawings, in which—

Figure 1 represents a side, and Fig. 2 a front, elevation of my improved jack, the pump-handle being shown partly broken away. Fig. 3 represents a vertical section of the same through line *y y* in Fig. 2. Fig. 4 represents a vertical section of jack-pump through line *x x* of Fig. 1. Figs. 5 and 6 represent the pump-valves *N* and *N'* shown in Figs. 3 and 4. Figs. 7 and 8 represent the packing-rings *d* of pump-piston shown in Figs. 3 and 4. Fig. 9 represents a horizontal section through the plunger and its casing and the pump and its auxiliary valve-chamber, the line *y y* passing through the plunger and its casing and the pump, the line *x x* passing through the pump and its auxiliary valve-chamber, and the line *z z* passing through the plunger and casing and the valve-chamber auxiliary to the pump. Fig. 10 is a vertical section of the plunger-space in central casting and the auxiliary valve-chamber, showing the duct through which the liquid passes from the latter to the former.

Upon a base-plate, *A*, is secured in any suitable manner a tubular casing composed of two parts, *A'* and *A*, held together by central

casting, *B*, of size and form suitable for the purposes hereinafter described.

Tubular casing *A* is provided with a cap, *a*, perforated to allow the free vertical motion of plunger *C*. Into the perforation in said cap *a* is inserted a plunger, *C*, extending, when in a state of rest in its lowest position previous to exerting lifting force, down through casting *B* into lower tube, *A'*, and provided at its top with a cap, *c*. Said plunger consists of a tube, and has inserted in it and securely fastened to its sides at any point at or near its center, but preferably at its center, a plug, *C*, which forms an abutment to prevent the passage of liquid from one part of the plunger to the other, and also the surface upon which is exerted the lifting-power of the liquid compressed in the space beneath. The lower end of the plunger is left open, in order freely to admit the compressed liquid and allow it to exert its lifting force upon plug *C*. For the same purpose any number of perforations may be made in the periphery of the plunger near its lower end. Immediately above plug *C* is a vent, *c*, in the plunger, for the passage and repassage of liquid between space *c* in the plunger and space *A* between the plunger and its upper casing, *A*, the external diameter of the plunger and the internal diameter of its casing being so proportioned as to give sufficient space between them to form, together with the space in the upper part of the plunger, a reservoir for the liquid used in operating the jack.

Central casting, *B*, has through it, in a line with the center of casing-tubes *A* and *A'*, a box of size suitable to admit and at the same time snugly confine plunger *C*, packing *t* being provided to prevent the escape of liquid from space *A* to space *A'*.

The upper and lower parts of the casing are joined to the central casting by means of screw-threads, or in such other suitable manner as to render them easily separable. Through the base-plate is a perforation provided with a screw-plug, *A*, for filling spaces *A* and *c* with liquid previous to working the jack. Caps *a* and *c* are provided with packing *a'* and *c'* to prevent the escape of the liquid.

The pump *D* consists of a chamber, *d*, *d'*,

(the former or lower part being situated in hollow screw-plug d' , and the latter or upper part in the body of extension D of central casting, B,) valve N in hollow screw-plug d' , piston E', snugly confined by packing-rings d^3 d^4 , and auxiliary valve-chamber B', with its valve N'.

The piston E' is operated by connecting-rods or bridle E and pump-handle F, working by means of its segment-gear F² in rack F', said handle and connecting-rods being held together and in place by screws f, the inner ends of which slide in recesses b⁶. The piston-packing is composed of alternate rings of metal and leather, or other flexible and elastic material, the internal diameter of the metal rings d^3 being less than the internal diameter of rings d^4 . This packing is held in place by screw-plug d.

G is a cock for opening and closing channel g', through which the liquid flows from the lower to the upper parts of the jack when the plunger is pressed down.

The operation of the jack is as follows: The upper and lower parts being filled with liquid by the removal of cap c and plug A⁴, and the plunger being at its lowest point, as shown in Fig. 3, upon raising piston E' the liquid is drawn from space c² through vent c⁴, and from space A⁶ through channel O, and, raising pump-valve N, flows into and fills chamber d³ d⁴. Thence, on the return-stroke of the piston, it is forced through channel n into auxiliary chamber containing valve N', and thence, by duct or channel m and space A⁷, into space c³ in the lower part of the plunger, where it exerts its lifting force upon plug or abutment C³, and thereby raises the plunger.

I claim—

1. In a hydraulic jack, the combination, with the tubular casing, of the tubular plunger having the transverse abutment, a communicating channel between the upper and lower chambers of the plunger, and a pump and valves for withdrawing the liquid from the upper chamber of the plunger and forcing it into the lower chamber thereof, so as to exert lifting force upon the abutment to raise the plunger, substantially as described.

2. In a hydraulic jack, the combination of the tubular casing, the tubular plunger fitted therein, so as to leave a space between the two, as described, said plunger having an upper and lower chamber separated by an abutment, the upper chamber being closed, except at a

port through which communication is permitted to the upper space between the plunger and casing, while the lower chamber of the plunger opens into the lower space between the plunger and casing, the channel leading from the upper space between plunger and casing to the lower space between plunger and casing, and the pump and valves for withdrawing the liquid from the upper chamber of the plunger and the upper space and forcing it into the lower space and the lower chamber of the plunger, so as to raise the plunger, substantially as described.

3. In a hydraulic jack, the combination of the tubular casing, the plunger having the upper and lower chambers and intermediate abutment, and fitted within the tubular casing, so as to leave an upper and lower space, as described, the passage communicating the upper space with the lower space, and the pump and valves for forcing the liquid through said channel, and a supplemental channel connecting the upper and lower space, and provided with a valve, which, when opened, permits the return of the liquid to the upper chamber of the plunger and surrounding space from the lower chamber of the plunger and surrounding space, substantially as described.

4. In a hydraulic jack, the combination of the tubular casing consisting of the central casting having the bore in which the plunger fits, and the channels of communication between the upper and lower tubular parts, with the upper and lower tubular parts of the casing detachably connected to said central casting, the detachable base and the tubular plunger, the whole arranged substantially as described.

5. The combination, with the casting B, having the channels m n o, of the detachable screw-plug d', having the recess in its end constituting a portion of the pump-chamber, the valves N and N', and the pump-piston, operated substantially as described.

6. The combination, with the casting B, of the pump-piston, the yoke E, the operating handle F, having the cogged inner ends, the racks F' on the casting, and the bolt-and-slot connection between the yoke and the pump-handle, substantially as described.

DANIEL DRAWBAUGH.
